UNITED STATES PATENT OFFICE.

FRANCES OLDENDORF, OF RIVERSIDE, CALIFORNIA.

DESIGN FOR AN OUTING AND SPORT HAT.

47,544.

Specification for Design.

Patented July 6, 1915.

Application filed March 2, 1915. Serial No. 11,563. Term of patent 3½ years.

To all whom it may concern:

Be it known that I, FRANCES OLDENDORF, a citizen of the United States, residing at Riverside, in the county of Riverside and State of California, have invented a new, original, and ornamental Design for Outing and Sport Hats, of which the following is a specification, reference being had to the accompanying drawing, forming part thereof.

The figure is a perspective view of an outing and sport hat, showing my new design.

I claim:

The ornamental design for an outing and sport hat, as shown.

FRANCES OLDENDORF.

Witnesses:

JAMES R. TOWNSEND.

ESTELLA HILL.
